UNITED STATES PATENT OFFICE.

DAVID LAZAR, OF LONG ISLAND CITY, NEW YORK, AND HARRY A. DREW, OF WEST NEW YORK, NEW JERSEY; SAID DREW ASSIGNOR TO SAID LAZAR.

COIN-CONTROLLED VENDING MACHINE.

Application filed March 16, 1923. Serial No. 625,659.

This invention relates generally to coin controlled vending machines and more particularly to a machine of this character, which is constructed of one or more separable units in such a manner that any desired number of units may be united together, and which is provided with a front cover piece being designed to fit over one or the desired number of united units, the cover piece being further provided with a coin controlled mechanism or mechanisms and a manifold coin conducting chute through which all coins are collected and guided to a collection chamber at the bottom of the vending machine.

The object of our invention is to provide a coin controlled vending machine of novel, simple, and efficient construction, having provision, first, whereby any number of individual units or containers may be united together to form a vending structure of any desired dimension; secondly, whereby any number of united units may be provided with a single front cover piece having a door for each container through which the articles to be vended may be discharged; thirdly, whereby the cover piece may be further provided with individual coin controlled door check releasing mechanism for each door; and fourthly, whereby the coins subsequent to being inserted in the door check releasing mechanism may be collected and conducted through a single manifold chute to a coin receptacle.

In the accompanying drawing which illustratively exemplifies one embodiment of our invention, Figure 1 is a perspective view of one unit of our improved vending machine; Fig. 2 is a longitudinal sectional view through the cover piece and adjacent portion of a single unit, the view being taken on line 2-2 of Fig. 3; Fig. 3 is a rear elevational view of the cover piece of Fig. 1; Fig. 4 is longitudinal section through a series of united units; Fig. 5 is perspective view of the coin controlled door check releasing parts; and Fig. 6 is a perspective view of the means employed to attach one unit to another; and Fig. 7 is a perspective view of the coin projector and portion of the coin chute adjacent thereto.

Fig. 8, is a side elevational view of a modified construction for attaching one unit to another and to suitable supporting and backing members; Fig. 9 is a plan view of a

unit showing the cover piece removed; Fig. 10 is a rear elevational view of the uppermost unit of a series of vending machines and showing the means carried by the units for engaging an adjacent wall to support the machines; Fig. 11 is a perspective view of the door releasing bar and a device actuated thereby for closing the coin slot subsequently to the contents of the machine having been discharged.

Referring to the drawings and particularly to Figures 1, 2 and 3, 10 denotes a rectangular casing or container having closed top and sides, open bottom and rear end wall. The front end of the casing is open to receive a cover piece 11 which comprises a front panel 12 and continuous upright wall 13 adapted to fit over a reduced flange 14 at the front end of the casing 10. The casing 10 is adapted to form a compartment 15 in which the article to be vended is disposed and the walls of this compartment project forward to meet the upright walls 16 about an opening 17 in the cover piece 11. The opening 17 serves to provide means through which articles may be placed within and discharged from the compartment 15. This opening 17 is closed by a hinged door 18 having a frame portion 19 composed of L shaped stock, the lateral flange of which is adapted to fit closely to the walls or casement 16 of the opening itself. The other flange of the frame 19 supports a glass panel 20 through which the contents of the compartment may be observed from the front of the vending machine.

The coin controlled door check releasing mechanism is mounted on the front cover piece 11 and comprises a coin slot 21 cut in the front plate at one side of the opening 17 on a place substantially level with the upper elevation of the opening. Secured to the rear face of the front panel 12 and leading from the slot 21 on a curve inwardly therefrom is a coin guide chute 22, the lower projection of the chute being directed downwardly and parallel to the front panel 12 and spaced away from the latter a distance equal to the height of the wall or casement 16. Adjacent the lower end of the chute 22 the latter is provided with an opening 23 through which the coin projecting mechanism operates and from the upper elevation of the opening 23 to the open lower end of the chute the overlying guide walls are re-

65

stricted to closely embrace opposite marginal faces of the coin disposed therein.

As shown in Figures 1, and 5 the coin A after being inserted in the slot 21 travels downwardly through the chute 22, and adjacent the lower end thereof further travel of the coin is prevented by the latter being brought into contact with a pair of stop rollers 24 and 25, both of which are disposed in cut out places at the opposite edges of the chute. The roller 24 is mounted on a fixed pin projecting inwardly from the inner face of the panel 12 and between the outside edge of the chute and the longitudinal wall 13 of the cover piece 11. The other roller 25 is mounted on one end of a slide bolt bar 26 which is slidably mounted beneath the bottom flange of the wall 16 and guided in suitable guide members 27. The far end of the bolt bar 26 extends to the outer face of the opposite vertical member of the wall 16 and is provided with an angular end portion 28 projecting a short distance up the side of the wall 16. The extreme end of the angular portion 28 carries a bolt 29 disposed parallel to the bar 26 and projects towards the opposite end of the latter, the bolt 29 being slidably in aligned openings 30 in the wall 16 and 31 in the adjacent wall of the door frame 19. The bolt 29 is yieldably held extended by means of a flat spring 32 engaged at one end to the wall 16 and the other end thereof being adapted to yieldably engage the bolt rod angular portion 28. Where a coin is forced past the rollers 24 and 25 the bolt rod 28 is projected to retract the bolt 29, the rod is held in retracted position by a spring actuated detent 33 disposed below the rod and adapted to engage against the shoulder of a notch 34 in the under surface of the rod 26. The notch 34 is provided with a straight upright wall forming the said shoulder and an inclined top wall directed downwardly in the direction of the movement of the rod to project the bolt 29. A key actuated mechanism 35, the details of which are not shown, is disposed on the panel 12 and provided with a tumbler which is adapted to be moved so as to engage with the detent 33 to release it from engagement with the shoulder of the notch 34.

The mechanism for projecting the coin in the chute 22 is disposed between the latter and the inner face of the panel 12 and comprises a finger button 36 mounted on the front face of the panel below the coin slot 21, the button being provided with an inwardly disposed stem 37 projecting transversely through a slot 38 longitudinally disposed in the front cover panel 12 and parallel to the side walls of the cover 11. The inner end of the stem 37 is mounted in a slide plate 39 overlying the inner face of the panel and projecting beyond the slot 38.

The slide plate 39 carries a U shaped member 40, the free ends of the parallel arms thereof being movable through a plane closely adjacent and parallel to the under surface of the chute 22. The slide plate 39 is normally and yieldably held so that the button 36 is disposed at the upper elevation of the slot 38, by a coiled spring 41, shown in Fig. 2. Pivotally mounted at the upper end of the U shaped member 40 and between the parallel walls thereof is a coin trigger 42 comprising a U shaped element fitting loosely between the parallel uprights of the other U member 40 and provided at its lower end with outwardly curved edges 43 terminating in projecting toe portions 44. When the slide 39 is retracted the toe portions 44 are disposed beneath the wall of the chute 22, see Figures 2 and 7, and at a point coinciding with the upper edge of the slot or opening 23, so that as the coin projecting trigger 42 is depressed the curved edges 43 will ride against the upper edge of the opening 23 and permit the toes 44 to enter the coin path under tension of a spring 45 disposed between the U member and the trigger. It will be apparent that the action of the toes 44 will be directed against the periphery of the coin A and at points thereon disposed above the rollers 24 and 25 upon which the coin is supported before being projected to retract the bolt.

It is to be understood that the mechanism described in the preceding paragraphs is identical for each unit, but if more than one unit is used and the dimensions of the cover plate are increased to cover a plurality of united units, as clearly illustrated in Fig. 4, the cover is provided with a manifold coin collecting and guide chute 46. The guide chute 46 is composed of the usual channel stock having the overlying flanges to prevent the coins from falling out when held in upright position, and extending the entire height of the cover piece 11. It is further disposed over and parallel to the coin chutes 22; and on a plane coinciding with the lower or discharge end of each chute 22 the back wall of the chute 46 is cut transversely thereof and to a substantial distance down both rear corners so as to permit the rear wall thus cut to be bent forwardly, i. e. toward the front panel 12, to a point where the lip of the tongue, designated 47, underlies the discharge end of the chute 22. Therefore, a coin subsequent to being ejected from the chute 22 will drop until it engages the tongue 47 and is guided inwardly into the chute 46. At the bottom or discharge end of the chute 46 the coins thus collected may be deposited into a drawer or other suitable receptacle shown diagrammatically in Fig. 4.

In Fig. 6, we have disclosed a proposed means of uniting the units to form a vend-

ing machine having a plurality of units. The top wall of a unit provides the bottom for a compartment 15 and the said top wall is provided with upstanding ears 49, which are slotted longitudinally thereof, i. e. parallel to the said top wall, and which are adapted to fit closely against the side walls of the next upper compartment. The slots in the ears are indicated 50 and are adapted to receive buttons 51 which are carried by the side walls of the upper casing. In order to assemble the casings 10 the members are merely superposed one above the other and the slots 50 brought into register with the buttons 51, whereupon the upper casing in each case is drawn forwardly until the buttons 51 are seated against the ends of the slots 50. The cover plate is then attached and locked in position by means of key controlled locks 53, the details of which are not shown, because any suitable type may be used, the bolts of the locks 53 being adapted to engage members disposed on the walls of the casings 10. It will be noted that after a number of casings 10 have been assembled and the front plate 11 attached that the casings themselves will not be capable of further relative movement in which case it will not be possible to disengage one casing from another.

Referring to Figures 8 to 10 inclusive, the construction of each unit 10^a is identical so as to enable any number of the same to be combined to form a complete vending machine. In this form of the invention the container for the article to be vended is designed as an integral part of the front cover member. The coin actuating mechanism will be identical with that shown in Figure 1 and is not shown in connection with Figures 8 and 9 for the sake of simplicity in the drawings.

The unit 10^a comprises a metal container or compartment 15^a integral with a front box shaped member 11^a and projecting rearwardly thereof. The member 11^a is greater in cross section than the container 15^a and is constructed of sheet metal having a rear marginal wall 11^b, side, top and bottom walls 11^c and a front wall 11^d having a centrally disposed opening 17^a to receive a door 19^a. The construction of the door and the means for operating the same are similar to those previously described. The side walls 11^c are provided on one side of the container with slots 100 which terminate at their lower ends in round openings to receive buttons 101 carried by an adjacent wall or supporting surface. The opposite side wall carries such buttons 101, as shown in Figure 9. The top wall of the box shaped member 11^a is provided along its front corner edge with a hook shaped bead 102, the open edge of which is directed towards the rear and which is adapted to engage a portion of a

superposed structure to which it may be attached. The lower portion of the front wall 11^d parallel with and closely adjacent the lower corner edge is provided with a channel 103 into which the hook-shaped bead 102 of an underposed structure is adapted to be engaged. As shown in Fig. 8, the two units 10^a are attached together by the bead 102 of the lowermost unit being engaged in the groove or channel 103 of the upper unit. The units are further attached to each other by means of coupling bars 104 comprising straight members having two or more openings to receive screws 105 which are adapted to screw into threaded openings in rear tabs 11^e and rear wall 11^b of the members 11^a.

When the desired number of units 10^a have been compiled in the manner described above a bottom unit 106 is attached to the lowermost vending unit 10^a. The unit 106 comprises a shallow compartment having an enlarged front portion provided with the hook shaped bead 102 along the upper front edge to engage the groove 103 of the superposed unit. The unit 106 is further provided with a coin drawer 107 into which the coins are collected by means of a manifold arrangement similar to that shown in Fig. 4, except that each unit will have its separate coin chute manifold which will register with the manifold chutes of the upper and lower units 10^a.

The units 10^a are disposed between manifold side walls 108, as shown in Fig. 9, which comprise flat members having either a flanged groove 109 disposed parallel to and closely adjacent the upright front edge to receive the buttons 101 of a unit, or a series of buttons 101 to be received by the openings or slots 100 of one side wall of the unit 10^a. The inside face of both side walls 108 is provided with a groove 110 to receive the tongue 111 of a back plate 112. After the units 10^a are assembled and the side walls 108 are arranged the back plate 112 is slid into position so as to bring the top on the same horizontal plane as the top of the side walls and top of the portion 11^a. The side walls are provided with upstanding centering pins 113 projecting from the upper edges thereof and the back wall or plate 112 carries one half of a stapple lock 114.

The final step of completing the vending machine consists in placing a top or cover unit 115 in position, which comprises a metal box shaped member having a front groove 103. The cover unit 115 is of a size sufficient to cover the entire underlying structure, as shown in Fig. 8, and is provided with a series of openings in the under surface adapted to register with and to receive the pins 113. The rear face of the top member 115 carries the other half of the stapple lock 114. It will be apparent that after the toe of the groove 103 of the top member 115

is inserted beneath the hook 102 and the cover placed so that the pins 113 enter their respective openings, that by locking the cover and back plate 111 together by means of the lock arrangement 114, the whole structure becomes an integral unit.

Referring now to Figures 2, 3 and 11, 116 denotes a slot closing device which consists of a lever cam piece 117 carried by the free end of the bolt bar 26 and an upright bar 118 having a level cam piece 119 at the lower end thereof and adapted to rest against the cam 117, for support. The upper end of the bar 118 projects to a plane slightly below the coin slot 21, at which plane it is provided with a plate 120 disposed at an angle thereto and against the inside surface of the front wall 12 or 11^a. A suitable guide member 121 is carried by the member 12 to embrace the upright slide bar 118. In the operation of the coin slot closing arrangement, the bolt 29 is operated in the manner previously described and in its movement the cam piece 117 will draw towards the cam piece 119 a movement which will cause the latter to rise and with it the plate 120 to cover the coin slot 21. Therefore, if a vending unit has been discharged of its contents any one is prevented from inserting another coin until the bolt bar 26 is reset.

Having described our invention what we claim is:

1. In a coin controlled vending machine, a container, a front cover panel therefor having an opening through which the articles to be vended may be passed, a hinged door for said opening supported in said cover, a coin slot disposed in the cover and coin chute leading downwardly therefrom, a coin ejecting device operating in said chute and comprising a yieldable trigger arrangement controlled from the outside of the cover and provided with slideable means to engage against a coin in the chute, and a door locking device operated by the forced movement of the coin by the operation of said trigger arrangement, the said device comprising a slideable bar provided with a bolt adapted to be moved through registered openings in the door and cover when the former is in closed position, means carried by the bar and disposed in the path of the coin through the chute for supporting the coin in the chute below the said trigger, whereby operation of the latter will move the bar to retract the bolt, and means for yieldably holding the bolt projected.

2. A coin controlled vending machine, as claimed in claim 1, including means for holding the bar and bolt in retracted position, substantially as described.

3. A coin controlled vending machine, as claimed in claim 1, including means for holding the said bar and bolt in retracted position after the coin is ejected, and means for

releasing said first means to permit the bar to reset itself after the door is closed, substantially as described.

4. A coin controlled vending machine, as claimed in claim 1, in which the said bar is provided with a notch having an inclined wall and a shoulder at the end thereof, a spring actuated detent adapted normally to engage the said shoulder when the bolt is retracted, and a key controlled arrangement cooperating with said detent to disengage the latter from the shoulder to permit the bar to reset itself, substantially as described.

5. A coin controlled vending machine, as claimed in claim 1, in which the means carried by the bar and disposed in the path of the coin in the chute comprises a roller adapted to move into and out of the chute through a slot in the edge of the chute, and a second roller having a fixed pivot supported in the cover and disposed in a slot at the opposite edge of the chute, whereby downward movement of a coin against said rollers will separate the first roller from the last roller and move the bar axially to retract the said bolt and release the door, substantially as described.

6. In combination a plurality of units adapted to contain articles to be vended, a front cover for said units, coin actuated releasing mechanism for each unit and carried by the said cover, the said mechanism comprising a chute for the coin and having a receiving and a discharge end, and a manifold chute overlying the chute for each releasing mechanism and being provided with tongues leading from beneath each of said discharge ends of the chutes and into openings in the manifold chute, whereby coins from each chute may drop onto the said tongues and be conducted into the manifold chute, substantially as described.

7. In a coin controlled door releasing mechanism a coin slot and chute, the latter being curved at the receiving end adjacent the slot and disposed in a right plane at substantially right angles to the axis of the slot, the discharge end of the chute being provided with a slot, a coin ejector controlled from the outside of the machine comprising a finger button, a saddle member connected to said button and guided in their movement by a slot in the vending machine, means for yieldably supporting the button at the upper elevation of the slot, a spring actuated coin trigger pivoted in said saddle member and provided with cam edge adapted to engage the upper edge of the slot in the chute to cause the engaging portion of the trigger to ride into and out of the path of the coin through the said chute, and a bolt bar slideable transversely across the general plane of the chute and provided with a projection extending into the path of the coin in the chute below the said trigger, the said bar be-

ing provided with a bolt to move into and out of engagement with the door of the vending machine.

8. In a vending machine as claimed in claim 1, the combination of a coin slot closing device, substantially as described.

9. In a vending machine, as claimed in claim 1, the combination of a coin slot closing device comprising an upright slide bar having a cam surface closely adjacent the 10 slide bar, a cam disposed on said slide bar and adapted to lift the said slide bar by

engagement with the first cam, and a plate carried by the slide bar and movable across the said coin slot to close the latter when the 15 said slide bar has been in operation to release the door of the compartment, substantially as described.

In testimony whereof, we, DAVID LAZAR and HARRY A. DREW, have signed our names 20 to this specification, this 26th day of February, 1923.

DAVID LAZAR.
HARRY A. DREW.
